COMBINED FOOD RECEPTACLE AND CHOPPING BOARD

John A. Russ, Massillon, Ohio

Application November 19, 1949, Serial No. 6,142

Term of patent 14 years

(Cl. D44—1)

To all whom it may concern:

Be it known that I, John A. Russ, a citizen of the United States, residing at Massillon, in the county of Stark and State of Ohio, have invented a new, original, and ornamental Design for a Combined Food receptacle and Chopping Board, of which the following is a specification, reference being had to the accompanying drawing, forming part thereof.

Figure 1 is an isometric view of a combined food receptacle and chopping board embodying my new design;

Fig. 2 is a side elevational view; and

Fig. 3 is a front elevational view thereof.

I claim:

The ornamental design for a combined food receptacle and chopping board, substantially as shown.

JOHN A. RUSS.
